DESIGN FOR A JEWELRY FINDING FOR CLIPS OR OTHER SIMILAR ARTICLES OF JEWELRY

Louise Davidson, New York, N. Y., assignor to Tabby, Ltd., New York, N. Y.

Application January 8, 1941, Serial No. 97,880

Term of patent 3½ years

To all whom it may concern:

Be it known that I, Louise Davidson, a citizen of the United States, residing at Hotel Earle, New York, in the county of New York and State of New York, have invented a certain new, original, and ornamental Design for a Jewelry Finding for Clips or Other Similar Articles of Jewelry, of which the following is a specification, reference being had to the accompanying drawing, forming part thereof.

In the drawing:

Fig. 1 is a front elevational view of a jewelry finding for clips or other similar articles of jewelry showing my new design; and

Fig. 2 is an edge view thereof.

I claim:

The ornamental design for a jewelry finding for clips or other similar articles of jewelry, as shown,

LOUISE DAVIDSON,
